UNITED STATES PATENT OFFICE.

JOHN DZIECH, OF CINCINNATI, OHIO, ASSIGNOR OF ONE-HALF TO CLARA FRANKENSTEIN, OF CINCINNATI, OHIO.

TAILOR'S PRESSING-MACHINE.

SPECIFICATION forming part of Letters Patent No. 705,826, dated July 29, 1902.

Application filed September 11, 1901. Serial No. 75,005. (No model.)

To all whom it may concern:

Be it known that I, JOHN DZIECH, a citizen of the United States of America, and a resident of Cincinnati, in the county of Hamilton and State of Ohio, have invented certain new and useful Improvements in Tailors' Pressing-Machines, of which the following is a specification.

The object of my invention is a tailor's pressing-machine with which the goose can be moved about over the cloth as freely as though held simply in the hand, and when desired a heavy pressure can readily be brought to bear upon the goose. This object is attained by the means described in the specification and illustrated in the accompanying drawings, in which—

Figure 1 is a side elevation of a machine embodying my invention attached to a table. Fig. 2 is a horizontal sectional detail view of the plate for coupling the machine to the table, upon an enlarged scale, taken upon line $z z$ of Fig. 1. Fig. 3 is a detail vertical sectional view of the swivel-joint upon an enlarged scale. Fig. 4 is a vertical section taken upon line $x x$ of Fig. 1. Figs. 5 and 6 are detail enlarged views of the tailor's goose, showing bar for coupling it to the machine.

Referring to the parts, standard A has a foot a for securing it to the floor and a vertical guide-bar a' for engaging a sliding plate B, which may be moved up and down upon the guide-bar to fit down upon and be secured to table-tops C of varying heights. In standard A above guide-bar a' is a vertical longitudinal slot a^2 , within which a lever D is swung upon a pivot d^3 . Lever D has upon its upper end two horizontal lugs d d' , between which arm E is pivoted upon a vertical pin e . Arm E has at its upper end two similar horizontal lugs e' e^2 , between which an arm F is pivoted upon a vertical pin f . Arm F has at its lower end a socket f' , into which a ball g upon a rod G fits. Rod G at its upper end is screw-threaded to receive a wing-nut g' and upon its lower end is bent into an arm g^2 ,

which fits beneath a bar h , secured upon top of goose H, being held therein by a pin g^3 , passed through its end. Above foot a standard A has a vertical longitudinal slot a^3 , within which is pivoted a foot-lever M, the short arm of which abuts against the downturned end of lever D and the long arm of which terminates in a foot-plate m . Lever D is upheld by a spring N, attached at one end to the lever and at the other to the end of a screw-threaded pin a^4 , which passes through standard A and has upon its other end a wing-nut a^5 , by which the tension of the spring may be regulated.

In use spring N is put at a tension, such that it will just sustain the weight of a tailor's goose, so that the muscles of the forearm are not tired in the operation of pressing by lifting the weight of the iron. By reason of the swivel-joint the iron can be pointed in any direction, and the double joints in the arms allow the tailor to move it in any direction, so that it is as freely moved in different directions as though held in the hand. Should it be desired to bring a heavy pressure upon the cloth at any point, the foot is pressed down upon plate m , which stands in a position conveniently reached.

What I claim is—

In a tailor's pressing-machine the combination of a standard, an upper and a lower lever pivoted to the standard each to swing in a vertical plane the lower lever bearing upward against the upper, a spring attached to the upper end of the upper lever and to the standard at a point above the lever, an arm coupled to the upper end of the upper lever to swing in a horizontal plane, and a second arm coupled to the free end of the first arm to swing in a horizontal plane, substantially as shown and described.

JOHN DZIECH.
